UNITED STATES PATENT OFFICE.

ALEXANDER A. SELKIRK, OF ST. LOUIS, MISSOURI.

DESIGN FOR A VOTING-BOOTH.

SPECIFICATION forming part of Design No. 26,227, dated October 27, 1896.

Application filed September 14, 1896. Serial No. 605,833. Term of patent 31 years.

To all whom it may concern:

Be it known that I, ALEXANDER A. SELKIRK, a citizen of the United States, residing at the city of St. Louis, State of Missouri, have 5 invented a certain new and original Design for Voting-Booths, of which the following is a full, clear, and exact description, reference being had to the accompanying drawing, forming a part of this specification, wherein 10 the figure represents a perspective view of a voting-booth configured and ornamented according to my new and original design.

This invention relates to a new and original design for voting-booths; and it consists in 15 the shape and ornamentation of folds which form the booth.

The booth is composed of three folds or walls A, each of which has two sunken panels B, of woven material. These sunken panels are about the same size in all of the folds 20 and are separated by a dividing cross-piece, as shown.

What I claim is—

The design for voting-booths, substantially as herein shown and described. 25

In testimony whereof I hereunto affix my signature, in presence of two witnesses, this 12th day of September, 1896.

ALEXANDER A. SELKIRK.

Witnesses:

HUGH K. WAGNER,
F. R. CORNWALL.
